Primary Examiner — Catherine A Tuttle(74) *Attorney, Agent, or Firm* — Conley Rose, P.C.(57) **CLAIM**

The ornamental design for a top hat game device, as shown and described.

DESCRIPTION

FIG. 1 is a top perspective view of the top hat game device showing my new design;

FIG. 2 is another top perspective view thereof;

FIG. 3 is a bottom perspective view thereof;

FIG. 4 is a side elevational view thereof;

FIG. 5 is a top plan view thereof; and,

FIG. 6 is a bottom plan view thereof.

The apparent variations in the length of the tether and dimensions of the securing element are due to their alternate positions shown in the different viewpoints.
